2004/0045796 A1 * 3/2004 Azzola et al. 200/50.01

FIG. 1 is a perspective view the circuit breaker;
FIG. 2 is a front view the circuit breaker;
FIG. 3 is a right view the circuit breaker wherein the broken line showing of the environment is for illustrative purpose only and forms no part of the claimed design.

FIG. 4 is a left view the circuit breaker;
FIG. 5 is a bottom view the circuit breaker; and,
FIG. 6 is a top view the circuit breaker.
